(57) CLAIM

The ornamental design for a cell sampler as shown and described.

DESCRIPTION

FIG. 1 is a perspective view of our new design.

FIG. 2 is a front view of FIG. 1 thereof;

FIG. 3 is a rear view of FIG. 1 thereof;

FIG. 4 is a left side view of FIG. 1 thereof;

FIG. 5 is a right side view of FIG. 1 thereof;

FIG. 6 is a top view of FIG. 1 thereof;

FIG. 7 is a bottom view of FIG. 1 thereof; and,

FIG. 8 is an enlarged view of FIG. 1 thereof; taken from the encircled portion "FIG. 8" in FIG. 1 thereof.

The dash-dash broken lines in the drawings depict portions of the cell sampler and are included to indicate a partially enlarged view and form no part of the claimed design.
